UNITED STATES PATENT OFFICE.

ADOLPH A. RACKOFF, OF DETROIT, MICHIGAN.

CONTAINER.

1,244,369.

Specification of Letters Patent. Patented Oct. 23, 1917.

Application filed February 28, 1916. Serial No. 80,963.

To all whom it may concern:

Be it known that I, ADOLPH A. RACKOFF, a citizen of the United States, residing at Detroit, in the county of Wayne and State 5 of Michigan, have invented certain new and useful Improvements in Containers, of which the following is a specification.

This invention relates to an improved container, one object of the invention being 10 the provision of a container, the body of which being made in any desired shape is composed of a fibrous material, the top edge being reinforced to receive a cover which may be made of metal or reinforced material, while the bottom is preferably metal 15 and is attached to the lower edge of the body by a dove-tailed joint.

A further object of the present invention is the provision of a novel reinforcing and 20 cover attaching member, band or ring, for fitting upon the upper edge of the body of the container, thus protecting the upper edge thereof and providing a seat for the rim of the cover, so that the edge of the 25 body is not worn or frayed by the constant attachment and removal of the cover.

A still further object of the present invention is the provision of a container, which is simple, durable and inexpensive in 30 construction, and thoroughly efficient and practical in use.

With the above and other objects in view, the invention consists of certain novel features of construction, combination and arrangement of parts, as hereinafter set forth, the spirit and scope of the invention, however, being limited only by what is claimed. 35

In the accompanying drawings:—

Figure 1 is a side elevation of a complete 40 cylindrical container, embodying my invention.

Fig. 2 is a vertical section thereof.

Fig. 3 is a top plan view of the container.

Fig. 4 is a plan view of the cover *per se*.

Fig. 5 is a plan view of the reinforcing ring or band, dotted lines showing the bending line thereof.

Fig. 6 is a partial elevation and sectional view of a modified form of reinforcing ring 50 or band.

Fig. 7 is a sectional view through a modified form of edge reinforcement and cover.

Referring to the drawings, the numeral 10 designates the body of the container, here 55 shown cylindrical, but which may be made

in any required shape, according to its use, such body being made of a fibrous material to facilitate the manufacture and cheapen the cost thereof. The lower edge 11, is flared outwardly to receive the inturned edge 12 of 60 the metal bottom cover 13. This joint is what I term a "dove-tail" joint.

The upper edge of the body 10 is provided with the circumferential bead 14, to assist in maintaining the reinforcing member 15 65 in place thereon.

This member 15 is made from sheet metal, and is folded on the line 16 so as to provide the substantially V-shaped in cross section band, the upper edge of the body being fit- 70 ted within the space between the member 15, so that the bead 14 will fit in the coöperating circumferential recesses 17 and 18 of the member 15. Thus the member 15 is in reality a clip to fit upon the upper edge. This 75 construction is clearly shown in Fig. 5, and is such as to receive thereon a plain metal cap or cover.

The band shown in the other figures has cut from the outer fold of the same, a plurality of tangs or tongues 19, which are bent upwardly to project above the upper edge of the member 15, so that when the cover 20 is in place the slits or slots 21 thereof will receive the tangs or tongues, which being 80 made of a bendable metal, may be bent outwardly and downwardly upon the outer face of the rim of the cover, thus securely attaching the cover in place.

The tangs or tongues being cut from the 90 portion of the member 15 which is bent upon the outer portion of the upper edge of the body 10, normally project upwardly and thus are in a natural position for projection through the slits or slots of the cover, 95 as the cover is fitted over the reinforced edge of the body 10. Thus the base of each tang or tongue is the fold line of the member 15.

It is apparent that this form of container may be made in any desired shapes, as oval, 100 square or rectangular, the upper edge being capable of reinforcement by a similarly shaped member 15, which is gripped by its own resiliency upon the upper edge of the body.

It will also be noted that the material of the body 10 is gripped securely between the recessed portions of the member 15, thus insuring a reduced metal mouth to the container, so that the rim of the cover will fit 110

snugly thereon and be securely attached after the container has been filled and covered.

The metal member 15 with or without 5 the tangs, tongues or fastening devices protects the upper edge of a fibrous body, so that the life of the same is greatly prolonged; permitting the attachment and removal of the cover without injury to the 10 body, at its upper edge, and adapting the present container for various uses, where a strictly fibrous container could not be used.

In Fig. 7 there is shown a slight modification wherein the member 15' which is in 15 the form of strip provided therein with gripping beads 21' and 22 at the free edges of said strip and this strip is bent on itself to straddle the edge 23 of the body 10' and upon compressing the bent portions the 20 beads 21' and 22 will engage the edge while formed spaced from the beads 21' and 22 are further beads 24 and 25, both being inwardly struck to provide an external channel 26 for the reception of the inwardly 25 struck bead 27 on the rim 28 of a cover 29. The bead 27 snaps into the channel 26 when the cover is applied and the rounded portion 30 of said cover fits snugly the corresponding portion of the member 15' at the bight 30 therein. The cover is provided with a circular depression 31 and is formed with a centrally upwardly struck knob 32 so that the cover can be readily detached or removed at will.

By this construction, the member 15' provides means that combines with the cover a very tight yet easily attached and removed cover.

Where found desirable the tongues 19 may be provided and thus an additional lock for 40 the cover will be had.

What I claim as new is:—

In a device of the kind described, in combination, a fibrous container, a bead formed upon said container, a metal reinforcing member having its parts doubled upon itself in contacting relation and bent to conform to said container, a series of tongues struck out from said member substantially upon the fold line and projecting in the direction 45 of the folded sides of said member, the free edges of said member being offset to form spaced apart beads between which is received and held the bead of said container, thereby causing the sides of said member 50 to continue the length of said container, and a metal cover embracing said member and formed with a series of slots through which said tongues project and may then be bent back over the outer side of said cover 55 so as to hold the latter against displacement.

In testimony whereof I affix my signature.

ADOLPH A. RACKOFF.
